UNITED STATES PATENT OFFICE

132,103

DESIGN FOR AN AIRPLANE KITE

Curtiss J. McCoy, Indianapolis, Ind., assignor to
Air-Line Mfg. Co., Inc., Indianapolis, Ind., a
corporation of Indiana

Application March 6, 1941, Serial No. 99,379

Term of patent 14 years

To all whom it may concern:

Be it known that I, Curtiss J. McCoy, a citizen
of the United States and a resident of Indian-
apolis, county of Marion, and State of Indiana,
have invented a new, original, and ornamental
Design for an Airplane Kite, of which the fol-
lowing is a specification, reference being had to
the accompanying drawing, forming part thereof,

In the drawing, Fig. 1 is a top plan view of an
airplane kite showing my new design, and Fig. 2
is a side elevational view of said airplane kite.

I claim:

The ornamental design for an airplane kite, as
shown.
